UNITED STATES PATENT OFFICE

NORMAN O. TREIN, OF LOS ANGELES, CALIFORNIA

TIME CONTROL MECHANISM

Application filed April 16, 1930. Serial No. 444,793.

This invention pertains to a time controlled mechanism adapted to be readily attached to time pieces already on the market, and also adapted to be used as an independent mechanism.

One object of the invention is to provide improved means for convenient attachment to an ordinary alarm clock which will control an electric circuit in such a manner that an electrically operated trip may be actuated by said circuit to stop or put into operation any independent mechanism, machine or device with which it is connected.

More specifically the invention relates to an improved electric switch which may not only be used in combination with an alarm clock, as aforesaid, but may also be advantageously used in other situations.

The electric switch provided by this invention may be readily connected with a clock, and may be used to turn off a radio at a predetermined time, thus enabling a person who desires to leave the radio set in operation at the time he retires for sleep to permit the sound or music produced by the radio to induce sleep and after a sufficient length of time to insure that this desired result has been produced the device will automatically shut off the radio from operation.

Other objects, advantages and features of invention may hereinafter appear.

Referring to the accompanying drawing which illustrates what is at present deemed to be a preferred embodiment of the invention,

Fig. 1 is a back view of an alarm clock showing the device attached thereto.

Fig. 2 is a section taken longitudinally through the device itself on line 2-2 of Fig. 1.

Fig. 3 is a section taken on line 3-3 of Fig. 1.

Referring in detail to the accompanying drawing, the clock casing 5, and clock alarm spring 6 may be of the usual construction.

In some cases the usual alarm spring shaft 7 will also be employed but in other cases it may be necessary to provide said shaft with an extension projecting a short distance beyond the back of the clock casing.

Attached to said alarm spring shaft 7 is a radial operating arm 8 and also a manually operable resetting arm 9. Said operating arm 8 is positioned to engage a movable switch arm 10 of insulating material which is pivoted at substantially its mid-length to the clock casing 5 by means of a pivot stud 11. By the side of switch arm 10, in a spaced, generally parallel relation thereto, a fixed switch arm or stationary switch base member 15, also of insulating material, is secured to the clock casing by any suitable means as by the screw threaded studs 16 which are provided with nuts 17. The movable switch arm 10 carries at one end a contact 10c and at its other end a contact 10d, while the stationary switch member 15 carries at one end a contact 15c and at its other end a contact 15d.

A small tension spring 20 has one end attached to the switch arm 10 and its other end anchored in any suitable manner, being shown as attached to the stationary switch member 15. This spring is attached to the movable switch arm 10 at a distance from its pivot 11, the strength of said spring being only such to bring the contacts 10d and 15d into engagement with each other when it is permitted to do so, it not being so strong as to overcome the action of alarm spring 6 which at times opens the contacts 10d and 15d and brings together the contacts 10c and 15c.

The contact 10c is connected with the line wire 25 by means of the wire 23, and the contact 15c is connected with the wire 24 of the battery 27 of the radio. The contact 10d, by means of wire 28 is connected with the line wire 25, and the contact 15d, by means of the wire 29 is connected to the radio 30. A switch 40 is provided on the wire 23 and a switch 41 controls the circuit through wire 28. The various circuits are completed by providing the additional line wire 35 which is furnished with a branch wire 36 leading to the battery 27. The radio set 37 is provided with the receiving compartment 30.

In operation, assuming the switches 40 and 41 to be closed, the alarm may be set to release the alarm spring 6 at the desired time

thereby to cause said spring at such time to operate the shaft 7 and radial arm 8 secured thereto. The operation of said arm 8, the free end of which engages the switch arm 10 5 below its pivot, will cause the contact points 10c and 15c to be brought together thus closing the circuit to the radio battery 27, at the same time separating the contacts 10d and 15d thus opening the circuit through the 10 radio and stopping the operation thereof presumably at an hour somewhat later than the person setting the alarm expects to have fallen asleep.

I claim:

15 In an electric switch, a pair of cooperating switch arms arranged in a generally parallel relation to each other, each of said arms carrying at each end a contact which is directed toward and is adapted to engage the 20 corresponding contact on the other arm, means to support one of said arms in a stationary manner, means to pivotally support the other of said arms between its ends, yielding means tending to draw the end portions 25 of said switch arms toward each other at one end of the switch and thus close the contacts at that end of the switch while opening the contacts at the other end of the switch, means to operate the switch in opposition to 30 said yielding means to close the last recited contacts and open the other set of contacts, said switch-operating means consisting of a spring arm, and a clock operatively related to said spring arm by means of a stem operable 35 by the clock and located between said switch arms.

In testimony whereof I hereunto affix my signature.

NORMAN O. TREIN.
